UNITED STATES PATENT OFFICE.

MILTON E. BRANTHAVER, OF SHADYGROVE, PENNSYLVANIA, ASSIGNOR TO THE AMERICAN MILLING AND REFINING COMPANY, A TRUST ASSOCIATION.

APPARATUS FOR THE TREATMENT OF ORES.

Application filed May 10, 1924. Serial No. 712,285.

This invention relates to certain improvements in apparatus for the treatment of ore, and more especially intended for use in the treatment of complex ores of the sulfide type and in a finely divided condition. One of its most important purposes is to provide a means by which ore may be continuously and economically subjected to a sulphatizing roast to remove the sulfur and like elements which render the ore more refractory and to convert the copper content of the ore from a sulfide to a sulfate, at a comparatively low temperature.

The foregoing and other purposes of the invention are carried out by the construction illustrated in the accompanying drawings, in which:—

Fig. 1 is a plan view, partly in section, of the preferred embodiment of an ore roasting furnace embodying my improvements;

Fig. 2 is a side view, partly in section, of said embodiment;

Fig. 3 is an enlarged vertical section on the line 3—3 of Fig. 2;

Fig. 4 is a plan view on a larger scale of a part of the traveling ore conveying means for forcing the ore from the receiving end of the furnace to the opening through which the treated ore is discharged from the furnace;

Fig. 5 is a view partly in elevation and partly in section of the parts shown in Fig. 4;

Fig. 6 is a view at one end of the furnace showing a specifically different means for conveying the ore within the furnace and discharging it through the outlet opening;

Fig. 7 is an enlarged section on the line 7—7 of Fig. 2;

Fig. 8 is an enlarged section on the line 8—8 of Fig. 1;

Fig. 9 is a detail representation of the valve for feeding the material into the furnace;

Fig. 10 is a sectional view of said valve; and

Fig. 11 is a detail view of the discharge end of the furnace and leaching pool in operative relation with the outlet opening at said end.

A designates the furnace which may be of any suitable shape and length. It is provided with a floor 10 and beneath said floor suitable heaters not necessary herein to set forth are arranged, in practice, preferably in the various places marked 11, having communication at one end of the furnace through

lateral openings 12, Fig. 8, with a chamber 13, which extends around the furnace at the discharge end of the latter and terminates in a stack 14 for carrying off the products of combustion. The roasting chamber within the furnace is marked A' and this chamber has communication, at the discharge end of the furnace, with the chamber 13, through suitably covered openings 15, whereby the volatile elements may be permitted to escape into the stack 14, when desired.

At the opposite end of the furnace, there is a hopper B which has communication with the chamber A', through an inlet opening controlled by a valve C. The hopper and the valve extend across the furnace, substantially from one side to the other. The valve C constitutes an ore feeder and is provided with peripheral openings c here shown as extending spirally of the valve and substantially throughout the length of the latter: the valve being thus so correlated with the inlet opening and hopper B as to feed the ore in a substantially constant stream and in a regulated manner into the ore-receiving end of the chamber A'.

D designates an endless traveling means having scrapers, such as those hereinafter described, operative to force ore continuously along the floor 10 of the chamber A' in a zig-zag course of travel from the receiving end of said chamber to the discharge opening 16 at the opposite end thereof, whereby the ore is opened up so that every particle thereof may be equally influenced by the heat and is maintained under the influence of the heat for a maximum length of time.

The preferred form of this traveling ore conveying means comprises two endless chains 20 and 21 connected at appropriate intervals by cross bars 22 each having at opposite sides of its transverse center two sets of blades 23 and 24, forming scrapers, rigidly secured thereto in any suitable way. The blades 23 of the set at one side of the center of each cross bar extend diagonally toward the right while the blades 24 at the opposite side of said center of each bar extend diagonally toward the left, and, moreover, the blades of successive bars are relatively so arranged that a set extending diagonally toward the right follows and is followed by a set extending diagonally toward the left.

In Fig. 6, a less desirable construction is shown. The latter comprising blades 120 car-

ried by a series of chains 121 arranged side by side, said blades being rigidly secured to the chain and those of each chain so set as to be directed alternately toward the right and left and to occupy a staggered relation with respect to the blades of adjacent chains.

10 Of course, it will be understood that the chains in either construction will extend around appropriate sprockets at the ends of the chamber A' and that suitable means will be provided to apply power thereto for imparting traveling movement to the chains and scrapers.

15 E designates a leaching pool or vat which is arranged at the opposite end of the furnace in such relation to the outlet opening 16 as to receive the ore which has been roasted and to seal said outlet against the entrance of air. The ore which has been deprived of its sulfur, 20 ammonia, arsenic and other highly volatile elements falls through the opening 16 and is immediately submerged in the water in said pool or vat E, the submersion of the ore as rapidly as it is delivered through the outlet opening 16 being assured by its coming in contact at this point with downwardly directed jets or streams of water emitted from a pipe 25, having communication with a suitable source of supply and arranged to supply 25 the cooling liquid at a place which is below the level of the floor 10 of the roasting chamber A' and above the level of the liquid in the pool, and to project the streams or jets of water into the heated ore at such an angle as to create a 30 downward draw in the pool. The bottom e of the vat inclines upward from the deepest part of the vat, which is below the discharge outlet 16 and a conveyor E' having scraper blades e' is operatively related to said floor, to carry 35 the gangue and metallic elements which are not in solution to and discharging the same over the top of the vat, along with the elements in solution.

40 It will be apparent from the foregoing that I have provided an apparatus for the treatment of ore in which the ore in a finely divided condition is fed continuously into the roasting chamber and is continuously conveyed along the floor of said chamber in a 45 zig-zag path and continuously discharged from said chamber into a leaching pool or vat and caused to be instantaneously submerged in the water of said pool or vat, and in which, moreover, the roasting of the ore is accomplished by radiant heat and in a chamber 50 substantially sealed against the access thereto of outside air, the feeding-in valve, together with the ore in the hopper and in the 55 grooves of the valve, serving to allow little if any air to enter through the inlet opening while the water in the leaching pool or vat serves to seal the discharge opening of the roasting chamber against the admission of air through said opening. It will also be apparent that the water in the leaching pool or

vat will be heated by the ore and that the ore will be correspondingly cooled by the water. The effect is to quickly and completely dissolve the copper sulfate and crack or break up the residue, it being noted in this connection 70 that copper sulfate is more readily dissolved in warm water than in cold water and that the co-efficient of contraction of the metallic substance contained in the ore is different from that of the silicious substances and similarly that the co-efficient of contraction of different minerals which may be contained in the ore is different from each other (i. e., one metallic substance will contract more at the same temperature than another metallic 75 substance with which it is intimately associated in the same silicious formation or gangue). Moreover, any steam generated by the submersion of the hot ore in the leaching pool will enter the roasting chamber through 80 the discharge opening and promote and expedite the volatilization of the sulfur, etc., and the conversion of the copper from a sulfide to a sulfate.

85 In short, the means described form a very desirable form of apparatus operative upon ore in a divided state, continuously supplied thereto, to deprive said ore of sulfur, etc., convert it from a sulfide to a sulfate at a comparatively low temperature, and continuously discharge it into a leaching pool, under 90 conditions which cause its copper content to be dissolved and bring about a partial separation of the various metallic ingredients from each other and of the metallic ingredients 95 from the silicious material and leaves the ore in a condition very favorable for subsequent operations intended to completely 100 separate the metallic ingredients from each other and hence for the recovery of all the values remaining in the ore after the sulfur and other such contents have been removed therefrom.

105 The furnace is provided with a chamber F, having communication with the roasting chamber A', to receive the sulfur and other comparatively highly volatile elements driven off in the roasting operation. These elements thus collected in the chamber F may be taken from said chamber and separated 110 from each other in any appropriate way and at any appropriate time.

115 Reference is hereby made to my companion co-pending applications filed in the United States Patent Office of even date herewith and numbered, respectively, 712,284 and 712,286. In application No. 712,284 I have shown, described and claimed the particular valve illustrated herein and in application No. 712,286 I have shown, described and claimed the particular leaching pool or vat illustrated herein, the said application being based upon the valve and leaching pool per se, respectively. Therefore, the valve 120 and the leaching pool are not herein claimed 125 130

broadly but are claimed in so far as they combine with the remaining features of the construction of this apparatus.

Having described my invention, what I believe to be new and desire to secure by Letters Patent, is:—

1. An ore roasting furnace comprising a roasting chamber having its floor provided with an ore discharge opening and an endless traveling conveyor in said chamber operative to force the ore under treatment along the floor of the roasting chamber and to discharge it through said opening, in combination with a leaching pool or vat operatively related to said discharge opening to receive the hot ore therefrom, and a liquid supply means operative to direct the liquid into the ore in its passage from the furnace.

2. An ore roasting furnace comprising a roasting chamber having its floor provided with an ore discharge opening and an endless traveling conveyor in said chamber operative to force the ore under treatment along the floor of the roasting chamber and to discharge it through said opening, in combination with a leaching pool or vat operatively related to said discharge opening to receive the hot ore therefrom, and a liquid supply means operative to direct the liquid into the ore in its passage from the furnace and in a direction which forces submersion of the ore in the pool or vat.

3. An ore roasting furnace having an ore inlet opening and the floor of its roasting chamber provided with an ore outlet opening, a conveyor operative to feed the ore along said floor in a zig-zag path and to discharge it through the outlet opening, a vat containing a cooling liquid arranged to receive the ore from said discharge opening, and means for injecting cooling liquid into the ore adjacent the discharge opening.

4. An ore roasting furnace having an ore inlet opening and the floor of its roasting chamber provided with an ore outlet opening, a conveyor operative to feed the ore along said floor in a zig-zag path and to discharge it through the outlet opening, a vat containing a cooling liquid arranged to receive the ore from said discharge opening, and means for injecting cooling liquid into the ore adjacent the discharge opening, and in the direction of the flow of said ore into the cooling liquid in the tank.

5. An ore roasting furnace having an ore inlet opening and the floor of its roasting chamber provided with an ore outlet opening, means operatively related to the inlet opening to feed the ore continuously into the roasting chamber and to substantially close said opening during the feeding operation, means in said chamber to feed the ore along the floor thereof and discharge it through the outlet opening, a liquid containing tank or vat to receive the ore from the discharge

opening, and means for injecting a cooling liquid into the ore adjacent the discharge opening, operative to cause steam to enter the roasting chamber.

6. An ore roasting furnace having an ore inlet opening and the floor of its roasting chamber provided with an ore outlet opening, means operatively related to the inlet opening to feed the ore continuously into the roasting chamber and to substantially close said opening during the feeding operation, means in said chamber to feed the ore along the floor thereof and discharge it through the outlet opening, a liquid containing tank or vat to receive the ore from the discharge opening, the level of the liquid in such tank being such that the discharge opening will be sealed against the ingress of outside air into the roasting chamber through said opening.

7. An ore roasting furnace having an ore inlet opening and the floor of its roasting chamber provided with an ore outlet opening, means operatively related to the inlet opening to feed the ore continuously into the roasting chamber and to substantially close said opening during the feeding operation, means in said chamber to feed the ore along the floor thereof and discharge it through the outlet opening, a liquid containing tank or vat to receive the ore from the discharge opening, the level of the liquid in such tank being such that the discharge opening will be sealed against the ingress of outside air into the roasting chamber through said opening, and means for injecting a cooling liquid into the ore adjacent the discharge opening and in a direction toward the bottom of the tank or vat.

8. An ore roasting furnace comprising a roasting chamber having an inlet opening and a discharge outlet, a collector having communication with the chamber to receive volatile elements given off in said chamber, a valve substantially closing the inlet opening and feeding the ore thereinto, traveling means for conveying the ore through said chamber and discharging it through the discharge outlet, and means arranged to inject a liquid into the ore and to cause the vapor formed to flow through the discharge opening and into the roasting chamber.

9. An ore roasting furnace comprising a roasting chamber having an inlet opening and a discharge outlet, a collector having communication with the chamber to receive volatile elements given off in said chamber, a valve substantially closing the inlet opening and feeding the ore thereinto, traveling means for conveying the ore through said chamber and discharging it through the discharge outlet, a vat containing a cooling liquid which receives the ore from the discharge opening and seals said opening against the ingress of outside air into the roasting chamber, and means to inject a cool-

120
125
130

ing liquid into the ore adjacent the discharge opening.

10. An ore roasting furnace comprising a roasting chamber having an inlet opening 5 and a discharge outlet, a collector having communication with the chamber to receive volatile elements given off in said chamber, a valve substantially closing the inlet opening and feeding the ore thereinto, traveling means for conveying the ore through said chamber and discharging it through the discharge outlet, a vat containing a cooling liquid which receives the ore from the discharge opening and seals said opening 10 against the ingress of outside air into the roasting chamber and means to inject a cooling liquid into the ore in a direction toward the bottom of the vat.

11. An ore roasting furnace comprising a roasting chamber having an inlet opening and a discharge outlet, a collector having communication with the chamber to receive volatile elements given off in said chamber, a valve substantially closing the inlet opening 20 and feeding the ore thereinto, traveling means for conveying the ore through said chamber and discharging it through the discharge outlet, a vat containing a cooling liquid which receives the ore from the discharge opening and seals said opening 25 against the ingress of outside air into the roasting chamber and means to inject a cooling liquid into the ore at a place above the level of the liquid in the vat.

35. 12. An ore roasting furnace comprising a

roasting chamber having an inlet opening and a discharge outlet, a collector having communication with the chamber to receive volatile elements given off in said chamber, a valve substantially closing the inlet opening 40 and feeding the ore thereinto, traveling means for conveying the ore through said chamber and discharging it through the discharge outlet, a vat containing a cooling liquid which receives the ore from the discharge opening and seals said opening 45 against the ingress of outside air into the roasting chamber and means to inject a cooling liquid into the ore adjacent the discharge opening and above the level of the liquid in 50 the vat.

13. An ore treating means, comprising a roasting chamber having an inlet opening and a discharge outlet and also having an outlet for volatile matter, a valve substantially closing the inlet opening and feeding the ore therethrough, traveling means for conveying the ore through said chamber and discharging it through said discharge outlet, 55 external means for heating the chamber, a liquid containing tank correlated with the ore discharge outlet to seal the same against the ingress of atmospheric air therethrough and to cause the ore discharged from the outlet to be submerged by the liquid in the tank, 60 means for causing a flow of liquid within the tank and a conveyor for discharging the ore from the tank.

In testimony whereof I affix my signature.

MILTON E. BRANTHAVER.
